US0D1001178S

(12) **United States Design Patent** (10) **Patent No.:** **US D1,001,178 S**
Eski (45) **Date of Patent:** **** Oct. 10, 2023**

(54) **CAMERA FILTERS WITH MOTORIZED LENS MECHANISM**

(71) Applicant: **Osman Eski**, Adana (TR)

(72) Inventor: **Osman Eski**, Adana (TR)

(**) Term: **15 Years**

(21) Appl. No.: **29/845,688**

(22) Filed: **Jul. 8, 2022**

Related U.S. Application Data

(62) Division of application No. 35/510,832, filed on Apr. 9, 2020 (U.S. filing date under 35 U.S.C. 384), and having an international filing date of Apr. 9, 2020, now Pat. No. Des. 960,222.

Primary Examiner — Richard E Chilcot

(74) *Attorney, Agent, or Firm* — Intellectual Property Law Group LLP

(57) **CLAIM**

The ornamental design for camera filters with motorized lens mechanism, as shown and described.

DESCRIPTION

FIG. 1 is a perspective view of camera filters with motorized lens mechanism, showing my new design;

FIG. 2 is a front view thereof;

FIG. 3 is a rear view thereof;

FIG. 4 is a bottom view thereof;

FIG. 5 is a top view thereof;

FIG. 6 is a left side view thereof; and,

FIG. 7 is a right side view thereof.

1 Claim, 5 Drawing Sheets
